UNITED STATES PATENT OFFICE.

ABRAM M. FELDMAN, OF NEW YORK, N. Y.

HEATING AND COOLING APPARATUS.

1,315,766.

Specification of Letters Patent. Patented Sept. 9, 1919.

Application filed November 7, 1918. Serial No. 261,449.

To all whom it may concern:

Be it known that I, ABRAM M. FELDMAN, a citizen of the United States, residing in the borough of Manhattan, city of New York, 5 and State of New York, have invented certain new and useful Improvements in Heating and Cooling Apparatus, of which the following is a specification.

My invention relates to combined heating 10 and cooling systems, and has for its object to provide a method and apparatus wherein the same system of piping and radiators may be employed either for heating a building or a plurality of buildings, or for cooling 15 the same.

In carrying out this object, my invention involves certain principles and details of operation, as hereinafter more definitely will be pointed out and claimed, reference being 20 had to the accompanying drawings, in which:—

Figure 1 is a sectional elevation of a portion of a building, illustrating my improved system in connection with what is known as 25 a one-pipe overhead down-feed water or steam heating system.

Fig. 2 is a similar view, illustrating my system in connection with an ordinary two-pipe steam heating system.

Fig. 3 is a detail sectional view of a check 30 valve of novel construction employed in connection with the one-pipe steam heating system.

Fig. 4 is a view similar to Fig. 1 and of a 35 similar system, illustrating a slight modification.

Fig. 5 is a view similar to Fig. 2, and of a similar system, illustrating a modification thereof.

Similar numerals of reference denote 40 corresponding parts in the several views.

Referring more particularly to Fig. 1, the reference numeral 1 denotes the floor line of the basement of the building, and 2 the 45 floors of the same. Located in the basement is the usual hot water heater 3 employed in hot water systems of this character, from the top of which leads a supply pipe 4 provided with a cut-off valve 5, said pipe 4 communicating with a vertical riser 6 leading to the top of the building, where it has attached thereto an air trap 7 of any well known construction. Extending in a downwardly inclined direction from approximately the upper end of the riser 6 is a pipe 8, which communicates with a down pipe 9 that in turn communicates through connect-

ing pipes 10 with the upper portions of ordinary hot water radiators 11, it being understood that the sections of said radiators have free communication at both top and bottom, as is usual in hot water systems. Leading from the bottoms of said radiators are the connecting pipes 12 which again communicate with the down pipe 9, said pipe having tapped thereinto a return pipe 13, which leads to the bottom of the heater 3, a suitable cut-off valve 14 and a check valve 14' being interposed in said pipe. This is the usual one-pipe overhead downfeed hot water system, and in its operation the hot water passes upwardly through the riser 6 to the top of the building, where any entrapped air from the entire system is removed through the trap 7, and the water 75 passes thence downwardly through the pipes 8 and 9 and into the tops of the radiators 11, being carried off, as the water cools in said radiators, through the lower connecting pipes 12 back into the pipe 9, and thence 80 through the return pipe 13 to the bottom of the heater 3 in the usual manner.

In connection with this system, I have provided a water cooling device 15 in the basement of the building, which may be of any suitable construction, and from which leads a suction pipe 16 valved at 17 and leading into a suitable force pump 18. From thence a pipe 19, valved at 20, leads to the pipe 9 of the system. Connected with the riser 6 is a pipe 21 valved at 22, and leading into the cooler 15, said pipe serving as a return for the cooling medium when the apparatus is used as a cooling system.

In operating as a hot water system, it will be understood that the valves 20 and 22 are closed and the valves 5 and 14 are opened, thus establishing communication through the water heater 3. When it is desired to use the system for cooling, the valves 5 and 14 are closed, thus cutting off the water heater 3, and the valves 20 and 22 are opened, thus establishing communication through the cooler 15 and the piping of the system. With the cooler in operation, the flow of 95 cooling medium through the system is the reverse of that which occurs when used as a heating system. That is to say, the cooling medium passes through the pipe 16 to the pump 18, by means of which it is forced 100 upwardly through the pipes 19 and 9, and enters through the pipes 12 upwardly into the radiators 11 where, in the process of extracting the heat of the air in the rooms of

the building, it is warmed. This results in the natural rising of the cooling medium in the radiators 11 and its flow out through the pipes 10 into the pipe 9, and from thence 5 through pipe 8 to the riser 6, which thus acts as a return pipe, the cooling medium passing downwardly through the same and through the pipe 21 back to the cooler 15. In order better to designate the opposite 10 directions of flow of the heating and cooling media, I have indicated the flow of the heating medium by full line arrows, and that of the cooling medium by dotted line arrows.

15 It is well known that cool air in a room descends, and that warm air ascends. It may be desirable, therefore, that the radiators, instead of being placed upon the floor of the room, be elevated some distance from 20 the floor, in order that, when the system is employed for cooling, the warm strata of air in the breathing zone of the rooms be brought into contact with the radiators in order to be cooled. This I have shown in 25 the left hand radiator of Fig. 1 of the drawings, the same being disposed some distance above the conventional location of the radiator, as shown by the right hand radiator.

It is necessary also that some provision 30 be made for taking care of the condensation of moisture from the room air on the surface of the radiators when the system is used for cooling, which I accomplish by disposing beneath the radiators 11 the pans 35 23, which will receive any drip from said radiators. Said pans are connected by suitable piping 24 with any point of discharge (not shown), such as a sink in the basement of the building.

40 While I have described Fig. 1 as a hot water system, it will be understood that the same may be operated as a steam heating system to heat the building in winter, known ordinarily as a one-pipe overhead downfeed 45 steam heating system, and may be converted into a cooling system employing water or brine for cooling in summer. When employed as a steam heating system, I provide on the return end of each radiator a check 50 valve 44 of novel construction and shown in detail in Fig. 3, and a thermostatic valve 25, tapped into the pipe 9 at a point below the radiators but above the heater. This thermostatic valve is provided with a suitable cut-off valve to cut it out of operation 55 when the system is used for cooling.

In Fig. 2 I have shown my improved system in connection with the well known two-pipe steam or hot water heating system. 60 The heating medium, steam or hot water, for said system is supplied through the pipe 26 from any suitable boiler (not shown), said pipe being valved at 27, and communicating with riser 28 leading to and communicating through connecting pipes 29

with the tops of radiators 30, the sections of said radiators, like the radiators 11 in the Fig. 1 construction, being in free communication at both top and bottom. Leading from the bottoms of said radiators are the 70 pipes 31, tapped into the return pipe 32, which communicates with return pipe 33, valved at 34, and returning to the boiler. Also tapped into the pipe 32 is a thermostatic valve 43 identical in structure and 75 function with the valve 25 of the Fig. 1 construction. Located in the basement of the building is a cooling apparatus, 35, from which leads a pipe 36, valved at 37, and leading into a suitable pump 38, from which 80 leads a pipe 39 communicating with the pipe 32 of the system. Leading from the pipe 28 of the system is a pipe 41, valved at 42, and leading back into the cooling apparatus 35.

85 The operation of this type of apparatus will be apparent from the construction, the steam or hot water, when used as a heating system, being supplied by the pipe 26 from the boiler, and passing upwardly through 90 the riser 28, and from thence through pipes 29 to the upper portions of the radiators 30, the return being through pipes 31 to the return pipe 32, and thence, through pipe 33, to the boiler. When it is desired to use 95 the system for cooling purposes, the valves 27 and 34 are closed, and the valves 40 and 42 opened. The system then may be filled with refrigerated water or other suitable cold liquid for cooling purposes, and with 100 the cooling apparatus 35 and the pump 38 in operation, the flow will be from the apparatus 35 through pipe 36 and pump 38 to the pipe 39, thence upwardly through pipe 32 and through pipes 31 to the bottoms of 105 the radiators 30, the water as it warms naturally rising in said radiators and flowing through pipes 29 to the pipe 28, through which a return is had through the pipe 41 to the cooler 35.

110 As in the Fig. 1 construction, I have shown the left hand radiator 30 elevated somewhat above the floor, and have also shown the drip pans 23 connected by piping 24 to a sink in the basement to carry off and condensation on the outside surface of the radiators. I also contemplate covering all the piping and fittings of either system with special non-conducting covering 115 of any suitable type.

120 In either of these systems, when the radiators are located on the floor line, as shown in the right hand radiators, it may be found desirable, when employing the system for cooling, to provide small fans disposed near the radiators to agitate the air in the rooms, in order that the warm air of the breathing zone may be brought into contact with the radiators for cooling the same.

125 It has been found desirable in connection 130

with this one-pipe downfeed steam heating system, as described in Figs. 1 and 4, to provide the return ends of the radiators with the self acting valves 44 opening freely to the discharge from the radiators but closing automatically against any entrance of steam. In Fig. 3 I have shown in detail my improved form of valve of this character, which is particularly well adapted for use 5 in connection with my improved heating and cooling system. The valve casing of my improved valve communicates through 45 with the radiator and discharges at 46. A check valve 47, swinging freely from a 10 pivot 48, acts automatically to close against return pressure through 46, while permitting an unobstructed discharge through the valve casing in a downward direction. Said valve is provided with an upwardly projecting lug 49, adapted to be engaged by a screw pin 50 located in the casing, the object of 15 said lug and pin being to provide means for moving and retaining said valve 47 in open position, shown in dotted lines, when the 20 system is to be used for cooling, it being understood that in this operation there must be an unobstructed flow of the water from the radiators 11 and 67 into the pipes 12 and 68, respectively. These checks also may 25 be found desirable to be used on the return ends of the radiators in the two-pipe system, shown in Fig. 2.

While I have shown the cooling apparatus 15 of Fig. 1, and 35 of Fig. 2 disposed in the basement of the building, it 30 may be found desirable, under certain conditions, to locate said apparatus at the top of the building, as shown in Fig. 4. In fact where the architectural provisions permit 35 such location of this apparatus it will be advantageous, in that it will be disposed more properly for the free circulation of the cooling medium downward from said apparatus through pipe 56, and will require 40 less power in the force pump 52 to circulate the cooling liquid through the system, as readily will be understood. In Fig. 4 I have shown this arrangement in connection with a one-pipe overhead downfeed 45 water or steam heating system, similar to Fig. 1 wherein the heater 51 and the pump 52 are located in the basement, and the cooler 53 is located at the top of the building. In this construction a pipe 54 valved 50 at 55 leads from the boiler, said pipe 54 communicating with the riser 56, valved at 57, and communicating through pipes 58 and 59 with the cooler 53 at its top and bottom, said pipes 58 and 59 being valved 55 at 60 and 61, respectively. Connected with the top of the pipe 56 is a pipe 62 upwardly inclined and communicating with a down pipe 63, a trap 64 being located at the upper end of said down pipe. Said down pipe 60 communicates through pipes 65 valved at

66 with the tops of the radiators 67, and return pipes 68 lead from the bottoms of said radiators back to said pipe 63, check valves 44, shown in Fig. 3, being employed in connection with said pipes 68. The pipe 63, 70 which is valved at 69 leads into the pump 52. A suction pipe 70, valved at 71, leads to the vertical riser 56. Also tapped into the pipe 63 above the pump 52 is a pipe 72 valved at 73, leading into the bottom of the 75 boiler. When the system is used for heating, the valves 60, 61, 69 and 71 are closed, and the valves 55, 57 and 73 are opened. The flow of hot water or steam passes through the system in the direction of the full line 80 arrows shown, rising first in pipe 56, passing down through pipe 63 and entering the tops of the radiators 67, passing out of the same through pipes 68 back to the pipe 63 and thence through pipe 72 to the boiler. 85 When the system is used for cooling, the valves 55, 57 and 73 are closed, and the valves 60, 61, 69 and 71 are opened. The flow is then from the cooler 53 through pipe 58 down through pipes 56 and 70 to the 90 pump 52, thence upwardly through pipe 63 and connecting pipes 68 to the bottoms of the radiators, the cooling medium rising in the radiators as it warms up and discharging through pipes 65 back to pipe 63 and 95 thence through pipe 62 into the cooler 53, the flow being indicated by the dotted line arrows. When the system is used as a steam heating system, it is desirable that a thermostatic valve 74, similar to the valves 25 100 and 43, be connected with pipe 63, as shown, and for the purpose hereinbefore described. In this construction, I have shown both the radiators 67 raised above the floors in the breathing zone of the rooms, though it 105 will be understood that they may be disposed on the floors, and suitable fans, hereinbefore described, used for air circulating purposes. It will be understood that when the system is used as a hot water system, 110 the cooler 53 at the top of the building may act as an expansion tank, in which event the valves 60 and 61 will remain open.

In Fig. 5 I have disclosed a modified 115 two-pipe system, wherein, although both the flow of the heating or the cooling medium is in the same direction through the piping, still it is reversed in the radiators, and the supply and return also are reversed. In said figure the reference numeral 75 denotes the boiler, from which a pipe 76, valved at 77, communicates with a riser 78, valved at 79 and 80, said riser communicating through pipe 81 with a cooler 82 at the top of the building. From said cooler 120 125 a pipe 83, valved at 84, communicates with a pipe 85 leading downwardly to a pipe 86, which communicates with the bottom of the boiler 75 and is valved at 87. Said pipe 86 also is valved at 88, and communicates with 130

the pump 89, which in turn is connected with the pipe 78, as shown. Radiators 90 are provided, the same communicating at their tops, through pipes 91, with the riser 78, and 5 at their bottoms, through pipes 92, with the pipe 85. In operation, when used as a heating system, the flow is from the boiler 75 through pipes 76 and 78, through the pipes 91, thence downward through the radiators 10 90 and through pipes 92 to pipe 85, and from thence through pipe 86 back to the boiler 75. When used as a cooling system, the flow is from the cooler 82 downwardly through pipe 85 and through pipes 15 92 into the bottoms of the radiators 90, thence upward through said radiators, and thence through pipes 91 to the riser 78, and back to the cooler 82. It will be understood that the system is filled with the 20 cooling fluid, and that the pump 89 serves to maintain the proper circulation of said cooling fluid throughout the system. It also will be understood that the natural flow of fluid from the cooler will be downward by 25 gravity through pipe 85, which will be assisted by the operation of the pump, and that the upward flow of the fluid as it becomes warmer, naturally will occur through the riser 78. It will be observed that in this 30 construction, although the supply and return is reversed, when converted from a heating into a cooling system, still the flow of the heating or cooling medium through the pipes 78 and 85 is in the same direction in both cases, although reversed in the 35 radiators. As in the other figures, I have indicated the flow of the heating medium through the pipes and radiators by full line arrows, and the flow of the cooling medium 40 by dotted line arrows.

I also prefer to employ on the radiators 90 when the system is used as a steam heating system, the check valves 44, and a thermostatic relief valve 93, said thermostatic 45 valve being disposed below the lowest radiator 90 and above the boiler 75.

It may be found desirable in warm climates, where no heat is used the year round, to install a cooling system alone, just as 50 heating systems are installed in cooler climate. It is understood that my invention in its broad aspect contemplates embracing the use of a cooling system alone. In fact, I make no claim for any novelty whatever 55 as to a hot water or steam heating system, the novelty being found entirely in its adaptation for use either as a well known heating system or as a cooling system involving my novel concept.

60 Having thus described my invention, what I claim as new and desire to secure by Letters Patent, is:—

1. A heating and cooling apparatus, com-

prising a pipe circuit, radiators connected therewith at top and bottom, the sections of 65 said radiators being in free communication at top and bottom throughout, a heater in said circuit, a cooler also in said circuit, and means in said circuit for cutting in the heater and cutting out the cooler, or vice 70 versa, the flow through the radiators when the heater is cut in being downward, and when the cooler is cut in being upward.

2. A heating and cooling apparatus, comprising a pipe circuit, radiators connected 75 therewith at top and bottom, the sections of said radiators being in free communication at top and bottom throughout, a heater in said circuit, a cooler also in said circuit, and means in said circuit for cutting in the 80 heater and cutting out the cooler, or vice versa, the flow through the system when the heater is cut in being in one direction through the pipe circuit and downward 85 through the radiators, and, when the cooler is cut in, reversed in the pipe circuit and upward through the radiators.

3. A one-pipe heating and cooling apparatus, comprising a closed pipe circuit, radiators connected with one side of said circuit at 90 top and bottom, the sections of said radiators being in free communication at top and bottom throughout, a heater in said circuit, a cooler also in said circuit, and means in said circuit for cutting in the 95 heater and cutting out the cooler, or vice versa, the flow through the system when the heater is cut in being in one direction through the pipe circuit and downward 100 through the radiators, and, when the cooler is cut in, being reversed in the pipe circuit and upward through the radiators.

4. A heating and cooling apparatus, comprising a pipe circuit, a heater in the bottom of said circuit, a cooler in the top of 105 said circuit, means for inducing a flow of heating medium from said heater in one direction through said circuit or for inducing a flow of cooling medium from said cooler in the opposite direction therethrough, 110 and radiators connected in said circuit at top and bottom, the sections of said radiators being in free communication at top and bottom throughout.

5. A cooling apparatus, comprising a 115 pipe circuit, radiators connected therewith at top and bottom, the sections of said radiators being in free communication at top and bottom throughout, a cooler in said circuit, and a pump also in said circuit for 120 maintaining the flow of cooling medium therethrough, the flow through the system being upward through the radiators.

In testimony whereof, I hereunto set my hand this 4th day of November, 1918.

ABRAM M. FELDMAN.
